GEORGE LOCKHART, OF NEW YORK, N. Y.

ELEVATOR-LOCK.

1,191,443.

Specification of Letters Patent.

Patented July 18, 1916.

Application filed May 10, 1911. Serial No. 626,145.

To all whom it may concern:

Be it known that I, GEORGE LOCKHART, a citizen of the United States, and resident of the city, county, and State of New York, 5 have invented certain new and useful Improvements in Elevator-Locks, of which the following is a specification.

The invention has for its object the closer and more positive control of an elevator car, 10 particularly when the car is at rest at a floor, either discharging or taking on passengers or freight.

In my previous application filed on or about the 13th day of February, 1911, and 15 bearing Serial #608,463, I have shown a means for mechanically retaining a car in a predetermined position. In this application I have enlarged upon that idea making the device much more complete and simple of 20 operation and making it perform other functions in addition to those set forth in that application.

One of the important new functions is to forbid the putting on of the power while 25 the car is locked in position, which I do in a very simple way as will be described, and another is the control of the landing door as well as the car door, which will also be set forth in fullest detail.

30 Other new and useful improvements will be enumerated as the specification progresses.

The following is what I consider the best means of carrying out this invention.

The accompanying drawings form a part 35 of this specification, in which—

Figure 1 shows in plan, an elevator car and a portion of one of the landings and landing gates. Fig. 2 is in elevation, viewed in the direction of the arrow 2, in Fig. 1. 40 Fig. 3 is in elevation, viewed in the direction of the arrow 3, in Fig. 1. Fig. 4 is in plan, a view showing a car of a different construction than that shown in Fig. 1, the operating mechanism being on the opposite side and 45 the gate opening from a different point. Fig. 5 is in elevation, viewed in the direction of the arrow 5, in Fig. 4. Fig. 6 is in elevation, viewed in the direction of the arrow 6, in Fig. 4, though showing a somewhat different construction. Fig. 7 shows in 50 detail a part removed, the same being on a

larger scale. Fig. 8 shows on a larger scale the latches used in the arrangement shown in Figs. 1 and 2.

Similar reference numerals indicate like 55 parts in all the figures where they appear.

In applying my device to the standard elevator cars, I have found that a single construction or design would not work well on all of the different types of elevators. I 60 have also found that the changes necessary although not involving new matter to any great extent requires such a re-arrangement of the parts as to make a single showing and single description of the details insufficient. 65 I have therefore shown in the drawing the device, the subject of this invention, secured to, and operable with two different types of cars, the one shown in Fig. 1, having the controlling means at the right hand, and 70 having the landing doors opening from right to left, and the one shown in Fig. 4 having the controlling means at the left hand, the landing doors opening from right to left, and provided with car doors also 75 opening from right to left.

Now referring to the figures, 1 indicates the floor of a car, and at 2 the landing floor is shown. The elevator shaft in which the car operates is inclosed by means of the grill 80 work 3 or by any other suitable means, and a door 4 which may be a single door, as shown in Fig. 1, provides a means for passage into or from the elevator shaft.

The car is operated and controlled by the 85 lever member 28 and may be provided with a folding gate or door 6, all of the ordinary construction.

An upright 7, carried by the car and supported between the floor and roof of the car, 90 carries an extension or shoe 8. The upright 7 is pivotally mounted in its supports and may be rotated through a part of a revolution, so as to project the outwardly extending end 9 of the shoe 8, over a landing floor 95 2. To turn the shoe into place it is necessary to raise the car to the level of the floor, or to a height that will allow the ball end 10 of the pin 11, to pass freely over the floor. The pin 11 is reciprocally mounted in the 100 shoe 8, and remains downward to an extent limited by the collar 12, by its own weight

and gravity. This pin insures that the car will be raised to the desired height before the door is opened, and should the car sink while discharging passengers, or while taking them on, the free motion of the pin 10 will not cause the shoe 8 to become jammed upon the floor, or work with a great friction thereon. The upright 7 carries a number of other members which will be described as 5 the specification progresses. The upward member 14, supported by the upright 7, has a collar pinned to the upright and extending therefrom an arm 15 which projects on a line parallel to the shoe 8.

15 Arranged at or near the top of the landing door frame is the duplex locking means comprising the latches 16 and 17, both operable by the projection 15. The inner latch 16 engages the pin 18 when the door is closed, securing the door in position, and the latch 17 rests upon the pin 18. When the arm 15 is rotated under these two latches it lifts the latch 16 thus freeing the door, and as soon as the door is moved carrying with it the pin 20 18, the latch 17 drops so that the notch 19 engages the arm 15, securing it in position until the door returns and the pin 18 lifts the latch 17 and frees the arm. The door is not secured however until the arm 15 is rotated 25 from its contact with the latch 16, allowing it to drop so that its notch 20 will engage the pin 18. The arm 15 should be flat, or if round of sufficient diameter so as not to engage in the notch 20. Another member carried by the upright 7, though near the base thereof is the arm 22, and pivotally engaged with the arm 22 is the link 23. A bell crank 24, supported by the lug 25 is connected to the link 23 and carries on its other arm a 30 pin 26. The partial rotation of the upright 7 through the arm 22, link 23 and bell crank 24, reciprocates the pin 26 in and out through a perforation in the guide casting 27, which supports and guides the upwardly extending 35 operating lever 28. The lever 28 is also provided with a perforation in register with the perforation in the guide casting so that when the pin 26 is reciprocated inward, it must pass through the perforation in the lever 40 member 28.

It will be seen from the construction just described that when the car is stopped at a floor, and the shoe is rotated so as to project outward over the floor, the latch of the landing gate will be released, not however before the power operating means has been securely locked, and it will be seen that as soon as the gate is open, even to a small extent, the shoe and the operating lever will be securely 45 locked in position to remain so until the gate is returned to a fully closed position.

To expedite the return of the gate to its fully closed position, I have arranged the peculiar counterweight shown in each of the 50 figures as secured to the gate, by means of the

pivot 30. The counterweight consists of the bowed arm 31, rotatably mounted upon the pivot 30 and carrying at its other end a properly weighted wheel 32. To operate the gate the arm 31 must be lifted to a small extent away from its engagement with the stop 33. The gate can then be pushed open, the wheel 32 running on the side wall of the elevator shaft or on a track provided for it. I prefer that it shall have an independent track because I have found that the device operates more conveniently if the upper end of the track be lifted slightly from the plane, so that the wheel 32 will be forced outward while traveling upward, then when the door 55 is pressed backward to the full extent there will be no forward pressure from the wheel 32, because it has reached the center of the pivot 30.

The construction shown in the remaining 60 figures although somewhat different from that just described is about the same in its operation although as the numerous changes may make it less easily understood, I will describe it in detail. The operator standing at 65 the left of the car, in easy reach of the handle 28', on the lever 28, would find it inconvenient to reach the ordinary operating handle 7' at mid-height of, and secured to the upright 7, for the purpose of rotating the 70 upright 7 and the parts carried thereby. I have therefore provided a lever 35, very similar to the operating lever 28, though provided with a projecting pin 36 at its lower end. The upright 7 is provided with an extension through the car and a right angled pin 37 is, by means of the link 38, connected to the pin 36, and is operated thereby. The link 38 is in this instance connected to the pin 36, and when the car has reached a 75 floor the operator bringing the lever 28 to a central position to stop the car, pulls the lever 35 to the right, thereby through the link 38, bell crank 24, and pin 26, locking the lever 28 in position. At the same time the link 38 has revolved the shoe 8, projecting it over the floor.

Modifications may be made within the scope of the appended claims without departing from the principle or sacrificing 80 the advantages of this invention.

It is obvious that other combinations or re-arrangement of the parts may be made as the occasion requires, or peculiarities of design may demand. Such a re-arrangement of the parts is shown in Fig. 6, in which the ordinary curved arm 31, and weighted wheel 32 are used to turn a lever 85 60 upon a pivot 61 by contacting in the upward motion with the pin 62 and in the downward motion with the pin 63. The movement of the lower end of the crank 60 draws forward a link 64 and rocks a bell crank 65 lifting a longer link 66, which in turn rocks the bell crank 67 forcing in- 90 95 100 105 110 115 120 125 130

ward the pin 68, which operates in a manner similar to the pin 26 to lock the power controlling lever.

Having carefully and fully described my invention what I claim and desire to secure by Letters Patent is.

1. An elevator lock having means for locking a car at a floor, a second locking means operable by the first said means for securing the power operating mechanism, and a releasing means for the gate, said releasing means controlled by and operable with said first locking means as herein specified.
- 15 2. An elevator lock having an upright, and a shoe carried by said upright, said shoe being provided with a reciprocating projection for preventing the operation of said shoe until the car has reached a predetermined position.
- 20 3. An elevator lock having an upright, a shoe carried by said upright, and operable over a floor, and an arm carried by said upright, a plurality of locking means operated by said arm and arranged, the one to secure the door, to be released by said arm, and the other to secure the arm, to be released by said door as herein specified.
- 25 4. In an elevator, a car, an upright carried by said car, a shoe carried by said upright and rotatable therewith, an arm carried by said upright and arranged at

right angles to said shoe and a link, a bell crank, and a pin connected together and operated by said arm and a power controlling means secured by said pin and by the rotation of the upright as specified.

5. In combination with an elevator car, an upright carried by said car, a shoe carried by said upright and rotatable therewith, an arm carried by said upright and a link, a bell crank, and a pin connected together and operated by said arm and a power controlling means secured by said pin and by the rotation of the upright as herein specified.

6. An elevator locking means having in combination a car, an upright carried by said car, a shoe carried by said upright and rotatable therewith, said shoe being provided with a reciprocating projection, an arm carried by said upright, a plurality of locking means operable by said arm and a second arm, and a power locking means operable by said second arm as herein specified.

Signed at New York city N. Y. this 24 day of April 1911, in the presence of two witnesses.

GEORGE LOCKHART.
